(57) **CLAIM**

The ornamental design for cosmetics case, as shown and described.

DESCRIPTION

FIG. 1 is a front perspective view illustrating my design for a cosmetics case;

FIG. 2 is a front elevation view thereof;

FIG. 3 is a left side view thereof;

FIG. 4 is a top view thereof;

FIG. 5 is a right side view thereof;

FIG. 6 is a bottom view thereof;

FIG. 7 is a rearview thereof; and,

FIG. 8 is a front perspective view in closed orientation.

The broken lines illustrate stitching on the cosmetics case and form no part of the claimed design.

1 Claim, 8 Drawing Sheets
